UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

STAND FOR MOVING-PICTURE MACHINES.

1,337,267.

Specification of Letters Patent. Patented Apr. 20, 1920.

Application filed October 12, 1915. Serial No. 55,409.

To all whom it may concern:

Be it known that I, NICHOLAS POWER, a citizen of the United States, and a resident of Brooklyn, in the county of Kings and 5 State of New York, have invented new and useful Improvements in Stands for Moving-Picture Machines, of which the following is a specification.

This invention relates to motion picture 10 apparatus and has for its principal object to provide an improved stand and motor driving connections for the projecting mechanism whereby the position of the mechanism may be adjusted to any desired 15 angle according to the altitude and direction of the apparatus above the screen on which the picture is projected.

A further object of the invention is to 20 provide a stand of this character in which accurate adjustments may be effected and the machine locked in its adjusted position without tools of any kind and while the machine is in operation, whereby the operator may determine by actual observation the 25 best position for the picture while making the adjustment.

A further object of the invention is to 30 provide an apparatus in which the adjustment and locking of the stand may be effected with one hand, leaving the other free to control the machine, and in which the machine is perfectly steady and held against vibration in all positions of adjustment and also while the adjustment is being effected.

35 A further object of the invention is to provide an apparatus of the class described embodying a motor drive having a change speed gearing supported on the fixed part of the frame with the projecting mechanism 40 and the projecting lantern on the adjustable frame, so arranged that the motor and change speed gear may remain in horizontal position during the adjustment of the apparatus to give the axis of projection the desired angle.

45 Further objects of the invention will be apparent from the following description and drawings wherein is illustrated a preferred embodiment of my invention.

50 In the said drawings, Figure 1 is a side elevation of my improved stand;

Fig. 2 is an end elevation looking from the right of Fig. 1;

Fig. 3 is a vertical section on enlarged scale through the center of the reel shaft. 55

Fig. 4 is a detail of the locking device.

Referring to the said drawings, 1 indicates the main stationary or base part of the frame which may be cast in a single piece and embodies an upper circular portion 2 having a central bore for the hub 3 for the adjustable part 4 of the main frame. The part 4 has a circular lower portion 4^a corresponding with the part 2 of the fixed frame member, and the part 2 is provided 60 with annular engaging friction faces as indicated at 5. Set in the face of the part 4 and equally spaced around the hub 3 are bolts 6 projecting through arcuate slots in the part 2. The two parts are yieldingly 70 clamped together by means of washers 7 on the bolts which are pressed against the adjacent face of the part 2 by means of stiff springs 8 surrounding the bolts between the washers and their heads. The springs 8 are 75 stiff enough to take up any lost motion in the pivotal connection between the two parts and also to cause the friction faces to offer considerable frictional resistance to their 80 relative adjustment.

The bottom of the part 1 consists of a substantially horizontal web 9 having attached to its under face a hanger 10 for the driving motor 11 and its change speed gearing. At each end of the web 9 are seats for the 85 outwardly inclined leg brackets 13, each of which is provided with two sockets to adjustably receive the legs 14 the sockets being set at sufficient angle to cause a large spread of the legs whereby the adjustment 90 of the machine will not shift the center of gravity of the apparatus materially away from over the center of the area of support. Each leg 14 is individually adjustable in its socket whereby the machine as a whole may 95 be lowered and raised by equally adjusting the legs, or the stationary part of the machine frame may be adjusted by proper relative adjustment of the several legs to accommodate irregular or inclined floors without affecting the angle of projection.

The adjustable part 4 of the frame com-

prises an open frame projecting in three directions from the circular part and having the contour of three sides of a square. The upper side of the square is complete and lies between the other two sides. This upper side 15 forms the support for the projecting mechanism or machine head 16 mounted near one end of the upper face. The two sides of the square form a bracket to receive the magazine 17 for the film reel on which the film is wound after it passes through the projecting machine. The reel is supported and driven through a shaft 18 supported in a ball bearing adjacent the journal 5 and passing through the hub 3, whereby the adjustment of the frame does not alter the position of the shaft. The shaft projects beyond the face of the part 2 and is provided with a driving pulley 20 loose on the shaft and having a clutch face 21 engaging a complementary clutch member 22 fast to the shaft the two clutch members being held in frictional engagement by means of a spring 23 engaging the outer face of the pulley and maintained under the desired tension by the adjusting and locking nuts 24 on the end of the shaft.

Projecting from the rear wall of the hollow square which supports the magazine 30 near the corner thereof are the track rods 25 for receiving the lamp house carriage 26. The lamp house carriage is adjustable along the rods in the unusual manner and comprises a pair of horizontal rods 27 on which the lamp house is adjustably mounted to thereby provide both lateral and longitudinal movement for the lamp. The outer ends of the rods 25 are supported by diagonal braces 28 extending to the lower corner of the rear side of the square, which form a convenient support for the switch box 29 containing the switches for controlling the electric motor and the projecting lamp.

45 For effecting the relative movement of the two parts of the frame to adjust the part 4 there is provided a screw shaft 30 pivotally attached to the rear leg bracket 13 and projecting through a threaded bearing 31 trunnioned on the rear wall of the square. The shaft 30 is provided with a handwheel 32 whereby it may be rotated to effect the adjustment. The frictional engagement of the two frame parts under the tension of the springs 8 will hold the part 4 against all vibration so that a single clamp is sufficient to rigidly lock the parts together after the desired position of the picture has been obtained. This clamp comprises a bolt 34 working in a bearing in an ear 35 projecting downwardly from the diagonal brace 28. The head of the bolt is square and lies in a channel formed on the inner face of an arcuate guide bar 36 65 projecting upwardly from the rear end of

the stationary part of the frame and concentric with the center of adjustment. The bar 36 is slotted to receive the shank of the bolt 34 and threaded on the end of the bolt is a hand wheel 37 whose hub acts as a clamp nut to clamp the ear and bar together in any desired adjusted position. The brace 28 is formed by spaced bars as shown more particularly in Fig. 2 to avoid interference with the bar 36 when the rear 75 end of the frame is lowered. By this arrangement the two adjusting wheels are conveniently positioned to be simultaneously grasped by the operator, or for either to be easily reached if the adjustment is effected while the machine is in operation, by the operator in his normal position at the machine.

The change speed gear comprises a frictional wheel on the motor shaft having a 85 peripheral driving face adapted to engage the flat face of the driven friction disk 38, which is supported in the carriage 39 to be adjustable in parallelism with the motor shaft to alter the point of engagement of 90 the disk and wheel with corresponding changes in speed. The power of the motor is transmitted to the moving picture machine by means of a pulley wheel 40 attached to the shaft of the disk 38 which 95 operates the driving pulley 41 of the machine head through the usual driving belt.

The operation of adjusting the machine will be readily understood from the above description. By means of the separately adjustable legs the frame is made perfectly steady with each leg supporting its share of the weight and with the main stationary part of the frame approximately level.

The clamping nut is then released by 105 means of the hand wheel 37 and the hand wheel 32 operated in the proper direction to shift the upper part of the frame in the bearing at the reel-shaft to raise or lower the illuminated area on the screen, as 110 may be desired. This movement is resisted by the frictional engagement of the two frame parts under tension of the springs 8, and as the screw shaft of the hand wheel 32 has a thread of low pitch, an exact adjustment can be had with the one operation. During the adjustment, the machine 115 may be operated to get the effect of the actual picture in various positions of adjustment, friction of the parts under the pressure of the springs being sufficient to hold the machine against vibration even while the frame is being adjusted. When the picture has been brought to the desired position, the two frame parts are clamped 120 rigidly together by means of the hand wheel 37.

The double adjustment permitted by the adjustable legs and the two-part frame allows the lower part of the frame to be 130

set level, even on an uneven floor, whereby the bearings of the motor carried by the base are relieved of the thrust of the weight of the motor which occurs when the motor 5 is on the adjustable part of the frame.

The arrangement of the center of adjustment at the point shown effects a substantial balancing of the weight carried by the adjustable frame at the angle of 10 inclination which is most common in the usual picture theater installation, the machine head and film magazines being obviously much heavier than the arc lamp and connections.

15 What I claim is:—

1. In a motion picture projecting apparatus, a supporting frame comprising a base part, adjustable means for supporting said base part, a machine carrying part, a motion picture projecting apparatus mounted on said part, a pivotal connection between said parts for permitting their relative angular adjustment, means for maintaining said parts in any position of relative adjustment, a motor for driving said apparatus mounted on said base part and driving connections between said motor and said apparatus.

2. In a motion picture projecting apparatus, a supporting frame comprising a base part, adjustable means for supporting said base part, a machine carrying part, a motion picture projecting apparatus mounted on said part, a pivotal connection between said parts for permitting their relative angular adjustment, means for frictionally opposing such adjustment, means for locking said parts in any position of relative adjustment, a motor for driving said apparatus mounted on said base part and driving connections between said motor and said apparatus.

3. In a motion picture projecting apparatus, a supporting frame comprising a base part, and a machine carrying part, a motion picture projecting apparatus mounted on said part, a pivotal connection between said parts for permitting their relative angular adjustment, a rotatable adjusting device for effecting such adjustment, means for locking said parts in any position of relative adjustment, a motor for driving said apparatus mounted on said base part and driving connections between said motor and said apparatus.

4. In a motion picture projecting apparatus, a supporting frame comprising a base part, and a machine carrying part, a motion picture projecting apparatus mounted on said part, a pivotal connection between said parts for permitting their relative angular adjustment, a threaded shaft having a bearing on one of said parts and provided with a nut attached to said other part for effecting such adjustment, means for lock-

ing said parts in any position of relative adjustment, a motor for driving said apparatus mounted on said base part and driving connections between said motor and said apparatus.

5. In a motion picture projecting apparatus, a supporting frame comprising a base part, and a machine carrying part, a motion picture projecting apparatus mounted on said part, a pivotal connection between said parts for permitting their relative angular adjustment, a threaded shaft having a bearing pivoted on one of said parts and provided with a nut pivotally attached to said other part for effecting such adjustment, means for locking said parts in any position of relative adjustment, a motor for driving said apparatus mounted on said base part and driving connections between said motor and said apparatus.

6. In a motion picture projecting apparatus, a supporting frame comprising a stationary base portion, legs adjustably supporting said base portion, a driving motor mounted on the base portion, an upper portion supporting the projecting mechanism, a pivotal connection between the two parts permitting relative angular adjustment, and a power transmitting connection between said motor and said mechanism.

7. In a motion picture projecting machine a supporting frame comprising a base part, a machine-carrying part mounted for pivotal movement on said base part for adjustment in a vertical plane, a motion picture projecting machine mounted on said machine-carrying part, a driving motor mounted on said base part, driving connections between said machine and motor, and means for frictionally opposing relative movement of said parts comprising engaging surfaces on said two parts, and means for pressing said surfaces together.

8. In a motion picture projecting machine, a supporting frame comprising a base part, a machine-carrying part mounted for pivotal movement on said base part for adjustment in a vertical plane, a motion picture projecting machine mounted on said machine-carrying part, a driving motor mounted on said base part, driving connections between said machine and motor, means for frictionally opposing relative movement of said parts comprising engaging plane surfaces at right angles to the axis of adjustment, and resilient means for pressing said surfaces together.

Signed at New York city, in the county of New York and State of New York, this 15th day of September, 1915.

NICHOLAS POWER.
